(57) **CLAIM**

The ornamental design for a see-through toaster, as shown and described.

DESCRIPTION

FIG. 1 is a front elevational view of a see-through toaster showing my new design in the environment of a toaster illustrated with dashed lines;

FIG. 2 is a back elevational view thereof;

FIG. 3 is a top plan view thereof; and,

FIG. 4 is a perspective view thereof.

The see-through toaster is particularly useful for toasting food to the desired completeness, and for avoiding excessive toasting of food, which may result in food waste. Viewing food as it is being toasted may provide a pleasurable culinary experience.

The broken or dashed lines showing environment is for illustrative purposes only and forms no part of the claimed design. Orientation descriptions of the feature elements using words "top", "front", or "back", are purely for illustration corresponding to specific drawings as filed and should not unduly limit the claimed design thereof.

1 Claim, 4 Drawing Sheets
